UNITED STATES PATENT OFFICE

EZRA M. UTTERBACK, OF CRESTON, IOWA

WHEELED SCRAPER

Application filed July 11, 1928. Serial No. 292,003.

The object of this invention is to provide an improved construction for a scraper of the type wherein a frame is mounted on wheels with a scraper pan swung below the frame.

A further object of the invention is to provide an improved machine for gathering a load of earth or the like, elevating the load by and through the advance of the machine, conveying the load to a desired location and there dumping it.

Still another object of the invention is to provide improved means for mounting a scraper pan on a wheeled vehicle.

15 A further object is to provide improved foot-actuated mechanism for controlling the filling, raising, dumping, and lowering of the scraper pan.

Another and further object of the invention is to provide improved means for automatically releasing the clutch mechanism employed for raising the load when the pan has reached a certain elevation.

20 Another object of the invention is to provide an improved scraper pan having a hinged gate at its rear end and an improved latch for holding it in closed position.

25 A further object is to provide an improved lever mechanism for unlatching the gate of the pan and permitting the load to be deposited.

30 A further object is to provide an improved combination machine for raising, conveying and depositing a load and for smoothing or leveling the substance after it is deposited.

35 Another and further object of the invention is to provide a machine of the character described, which is simple yet sturdy in build, particularly efficient in use, and not composed of complicated mechanism which would be apt to get out of order.

With these and other objects in view my invention consists in the construction, arrangement and combination of the various parts of my device, whereby the objects contemplated are attained, as hereinafter more fully set forth, pointed out in my claims, and illustrated in the accompanying drawings, in

50 which:

Figure 1 is a rear elevation of my improved wheeled scraper.

Figure 2 is a longitudinal section of the same on the line 2—2 of Figure 1, the dotted lines indicating the position of some of the parts when the scraper pan is in elevated position.

Figure 3 is a detail section through the clutch mechanism on the line 3—3 of Figure 1.

Figure 4 is a further detail of the clutch mechanism on the line 4—4 of Figure 3.

Figure 5 is a detail sectional view indicating the means for automatically releasing the clutch mechanism.

Figure 6 is a plan view with portions broken away, illustrating the combination of my improved scraper with a smoothing and leveling blade.

Figure 7 is a side elevation of the combined machine shown in Figure 6.

Figure 8 is a detail sectional elevation of an escapement device provided in connection with my machine.

In the accompanying drawings, I have employed the numeral 10 to designate generally, a frame, the forward end of which is supported upon a pivoted axle 11. Wheels 12 are journaled at the ends of the axle 11 and a tongue 13 is connected in any suitable manner with the intermediate portion of said axle.

Figure 14 is journaled for rotation at the rear portion of the frame 10 and wheels 15 are mounted upon the ends of the axle 14.

I prefer to employ the usual ratchet escapement devices for the wheels 15, as shown in Figure 8, including an annular ratchet 16 fixed to the shaft 14 and a pawl 17 pivoted to the wheels 15 and held in engagement with the ratchet by a spring 18.

This arrangement provides an operative connection between the wheels 15 and axle 14 when the wheels are turning in a forward direction, but permitting the wheels to escape the axle when turning in a rearward direction.

At its rear end the frame 10 is formed with a downwardly extending portion 10' and substantially L-shaped brackets 19 are fixed at

60

65

66

70

75

85

90

95

100

opposite sides of the frame and connect an intermediate part of the horizontal portion thereof with the lower part of the downwardly extending portion 10'.

5 A scraper pan 20 is mounted below the frame 10 and has its forward portion pivotally connected by links 21 with the brackets 19 at points adjacent the angles of said brackets.

10 Rearward links 22 are pivoted to the rear portions of the sides of the pan 20 and to downwardly extending ears 23 carried by intermediate parts of the horizontal portions of the brackets 19.

15 By this arrangement, the scraper pan 20 is pivotally mounted to the brackets 19 by two pairs of links and the pivotal connections of the rearward links are lower than the pivotal connection of the forward links so that when 20 the pan is elevated its rear end travels upward more rapidly to clear the ground.

The pan 20 is open at its top and at its forward end and is provided with a suitable cutting or scraping edge. The pan 20 is also 25 open at its rear end, but is normally closed by a hinged gate 24.

The gate 24 carries ears 25 at its upper margin which are pivoted on a hinge rod 26 extending transversely of the pan.

30 The latching means for the gate 24 includes a pair of latch rods 27 and 28 loosely mounted in keepers 29 and 30 carried by the lower portion of the rear face of said gate. Each of the latch rods 27 and 28 projects at one end 35 beyond a side margin of the gate and is adapted to engage an upwardly opening hook member 31 or 32 carried by and projecting rearwardly from the adjacent side wall of the pan 20.

40 Bell crank levers 33 and 34 are pivoted on the rear face of the gate 24 and each of said bell crank levers has one of its arms pivotally connected to the inner end of one of the latch rods 27 and 28.

45 Links 35 and 36 are pivoted to the other arms of the bell crank levers and are pivotally attached at their opposite ends to an intermediate portion of a lifting lever 37 fulcrumed on the rear face of the gate 24 and 50 having its free end loosely received within a keeper 38 carried by said gate.

Suitable means which is hereinafter described, is provided for lifting the lever 37, oscillating the bell crank levers 33 and 34 through the links 35 and 36, and thereby causing an inward movement of the latch rods 27 and 28 to withdraw them from the hooked members 31 and 32 and permit the gate to swing open.

60 A bail or yoke 39 is pivoted to the forward end of the pan 20 and has attached thereto, a flexible draft member such as a chain 40 which extends forwardly and is adjustably connected to the rear end portion of the 65 tongue 13 over the front axle. The draft

member 40 may be shortened or lengthened, as desired, thus controlling the depth of cut of the scraper pan.

Ears 41 are fixed to and project forwardly of the forward end of the scraper pan 20 and elevating members such as chains 42 and 43 are fixed to said ears and extend upwardly over pulleys 44 carried by an intermediate portion of the frame 10. The chains 42 and 43 then extend rearwardly and downwardly and are fixed to and adapted to be wound upon drums 45 and 46, which are normally loose on the rear axle 14.

The clutch mechanism for operatively connecting the drums 45 and 46 with the axle 14 forms the subject matter of my companion application filed July 11, 1928, Serial No. 292,004, but I have here shown and will describe enough of such of said clutch mechanism that the operation of the machine may be understood.

Suitably fixed to the axle 14 adjacent the inner faces of the drums 45 and 46 are clutch members 47 and 48, each of which has pivotally mounted on one face, a pair of pawls 49, the pivots of which are indicated at 50 (see Figure 3). The pawls 49 project within a recess 51 formed in the adjacent face of the adjacent drum, such as 45 in Figure 3, and each of said pawls is formed with a projection or tooth 52 adapted for operative engagement with internal teeth 53 formed peripherally of the recess of the drum.

Slidably mounted in the clutch member, such as 47, are a pair of plungers 54, each formed with an inclined end portion adapted to engage a pivoted roller 55 carried by one of the pawls 49 and arranged to move said pawls through an arc so that the teeth 52 will engage the internal teeth 53 of the drum and thereby cause an operative engagement between the clutch member and the drum.

55 Springs 56 are fixed to the free ends of the pawls 49 and to ears 57 carried by the clutch member to normally hold said pawls out of operative engagement with the drum.

The opposite ends of the plungers 54 project from the clutch members 47 and 48 and are engaged by sleeves 58 and 59 loosely mounted on the shaft or axle 14. The plungers 54 are provided with coil springs 60, which are designed to withdraw them from the recesses of the drums when pressure has been released.

60 Loosely mounted on the central portion of the axle 14 are cooperating clutch actuating members 61 and 62, which contact with each other and with the sleeves 58 and 59 respectively. The clutch actuating member 61 is formed with inclined faces adapted to engage projections 63 on the other clutch actuating member 62, whereby said clutch actuating members are forced apart when they are rotated oppositely, thus exerting pressure

upon the sleeves 58 and 59 and causing them to project the plungers 54 toward and within the drums 45 and 46 to clutch said drums to the axle 14 through the means just described.

A rock shaft 64 is journaled on the portion 10' of the frame and said rock shaft is formed with spaced rearwardly extending crank arms 65 and 66. The crank arm 65 is pivotally connected by a link 67 to an ear 68 on the forward side of the clutch actuating member 61, while the crank arm 66 is pivotally connected by a link 69 with an ear 70 on the rearward side of the clutch actuating member 62. When the rock shaft 64 is rotated in such manner as to raise the crank arms 65 and 66, an upward pull is exerted upon the links 67 and 69 which causes a slight opposite rotation of the clutch actuating members 61 and 62, thus forcing said members apart with the result previously mentioned.

A shaft 71 is journaled transversely of the frame 10 in front of the operator's seat 72. A clutch pedal lever 73 is pivotally mounted on the shaft 71 and is designed for operative engagement with a clutch lever 74 also loosely mounted on said shaft and extending rearwardly therefrom. This operative engagement may be by means of a lug or shoulder 75 on the pedal lever 73 adapted to engage a lug or shoulder 76 on the forward end of the clutch lever 74.

Pivotally connected to the rear end of the clutch lever 74 is a link 77 which extends rearwardly and has a pivotal connection to an arm 78 fixed to the rock shaft 64. When foot pressure is applied to the pedal lever 73 it raises the clutch lever 74 to the position shown by full lines in Figure 5, thereby exerting a pull upon the link 77 and through the arm 78 rotating the rock shaft 64 forwardly so as to exert an upward pull upon the links 67 and 69 to operate the clutch actuating members 61 and 62.

This causes the drums 45 and 46 to be clutched to the axle 14 and thereupon, forward travel of the machine will cause the chains 42 and 43 to be wound upon the said drums, whereby the scraper pan 20 is raised to the position shown by dotted lines in Figure 2.

It is assumed of course, that this action usually takes place after the scraper pan 20 has received a load through forward advance of the machine.

A releasing rod 79 is journaled transversely of the frame below the shaft 71 and said rod is formed with a downwardly extending crank or offset portion 80, which is adapted to be contacted by the forward portion of the scraper pan 20 when said pan approaches its upward limit of movement.

The release rod 79 also is formed with an upwardly extending crank or offset portion

81, which is adapted to be engaged and embraced by a hook member 82 formed on and extending forwardly from the clutch lever 74, when said clutch lever is moved forwardly to operative position, as hereinbefore described.

When the scraper pan 20 engages the downwardly extending crank portion 80, it moves said crank portion rearwardly, as indicated in Figure 5, thus rocking the release rod 79 and moving the upwardly extending crank portion 81 forwardly, thus pushing the hook member 82 upwardly and returning the clutch lever 74 to the inoperative position indicated by dotted lines.

Thereupon, the springs 60 act to withdraw the plungers 54 and the springs 56 act to withdraw the pawls 49, so that the clutch mechanism is automatically moved to inoperative position and upward movement of the scraper pan ceases.

I prefer to provide means to insure that the rotation of the drums 45 and 46 will be synchronized so that uniform pull or tension is exerted upon the chains 42 and 43 at all times. This means includes a counter shaft 83 journaled at the rear of the frame and having pinions 84 and 85 fixed thereto and meshing with external gears 86 and 87 formed on the respective drums.

I also provide means for normally preventing reverse rotation of the drums 45 and 46 and for thereby maintaining the load in elevated position. This means includes ratchet wheels 89 and 90 formed on the respective drums and engaged by gravity pawls 91 and 92 pivoted on the frame portion 10'.

The means for opening the gate 24 and permitting the load of the scraper pan to be deposited includes a pedal dump lever 93 loosely mounted on the shaft 71. The dump lever 93 is formed with a rearwardly extending arm 94 substantially at right angles thereto and a link 95 is pivoted at one end to said arm and extends rearwardly where it is pivoted at its opposite end to a lever 96. The lever 96 is fulcrumed between its ends at the rear of the frame portion 10' and fixed to its lower end is a draft member, such as a chain 97, which is attached to an intermediate point of the lifting lever 37.

When the pedal dump lever 93 is pressed forwardly by the foot of the operator, the arm 94 thereof is moved upwardly, exerting a pull on the link 95 and oscillating the lever 96 to the end of raising the lifting lever 37 through the draft chain 97. Upward movement of the lifting lever 37 causes the latch rods 27 and 28 to be withdrawn and permits the gate 24 to swing rearwardly on the hinge rod 26 so that the load may be deposited from the rear end of the scraper pan.

The means for permitting the pan 24 to be lowered includes a pedal lever 98 fixed to

the shaft 71, which shaft is formed at its ends with cranks 99 and 100. Links 101, 102 pivotally connect the cranks 99 and 100 with the gravity pawls 91 and 92 respectively. Forward pressure on the pedal lever 98 causes an oscillation of the shaft 71 and a pull on the links 101 and 102 through the crank arms 99 and 100, thus lifting the pawls 91 and 92 out of engagement with the ratchet wheels 89 and 90. This frees the drums 45 and 46 and permits the scraper pan to move by gravity to lowered position.

As the pan 20 assumes its lowered position, the gate 24 swings back to place across its rear end and the projecting ends of the latch rods 27 and 28 strike the hook members 31 and 32, which are inclined at their rear ends. As the latch rods 27 and 28 are pivoted at their inner ends and have a freedom of movement in the keepers 29 and 30, their outer ends are permitted to move upwardly, as indicated by dotted lines in Figure 1, until they enter the upwardly opening hooks of the members 31 and 32, after which said latch rods drop into position within said hook members and the gate is thus latched.

The seat 72 for the operator is placed above the frame 10 where he is out of the dirt and dust and where he can easily reach the control levers and since all of the controls are arranged for foot actuation, it follows that the driver has both hands free at all times for other purposes.

It is apparent that I have designed a wheel scraper which is compactly arranged and which is of sturdy and dependable construction and is especially efficient for receiving, lifting, conveying, and depositing a load with a minimum of time and labor as compared with the results accomplished.

In Figures 6 and 7, I have illustrated a modified form wherein provision is made for mounting a smoothing and leveling blade on the frame in front of the scraper pan.

In this construction the mechanism is the same as previously described, but the frame 10^a is lengthened to accommodate the blade, which is designated by the numeral 103. The blade 103 is carried by an auxiliary frame 104 having a forwardly and upwardly extending beam 105 removably attached at its free end to a hook 106 carried by the rear end of the tongue 13 of the machine. The auxiliary frame 104 may also be attached by means of chains 107 and 108 to the forward end of the frame 10^a and by rearwardly extending chains 109 and 110 to the brackets 19 at opposite sides of the main frame.

Standards 111 and 112 are fixed to and rise from the auxiliary frame 104 near the respective ends of the blade 103 and the upper ends of said standards are pivotally connected by links 113 and 114 to the forward end of the main frame 10^a.

Hand wheels 115 and 116 are mounted in

longitudinal planes at opposite sides of the main frame and are fixed respectively to worm shafts 117 and 118 journaled transversely of the frame in front of the driver's seat 72.

Control shafts 119 and 120 are journaled longitudinally at opposite sides of the frame and said shafts are provided with worm gears 121 and 122, which mesh respectively with the worms of the shafts 117 and 118. At their forward ends, the control shafts 119 and 120 are formed with cranks or offset portions 123 and 124 respectively, which pivotally engage the upper ends of stems 125 and 126 projecting upwardly from the standards 111 and 112. The stems 125 and 126 preferably are not rigidly attached to the standards, but extend loosely therethrough and are cushioned by means of coil springs 127 mounted thereon and engaging the upper ends of said standards and set collars 128 carried by the stems.

Set collars 129 are also fixed to the lower ends of the stems 125 and 126 and said set collars engage beneath flanges or ears 130 on the upper ends of the standards 111 and 112 through which flanges or ears the stems are slidably extended.

When either of the hand wheels 115, 116 is rotated in one direction, it causes a rotation of its control shaft 119 or 120 and a downward pressure on the adjacent stem 125 and 126 through the crank of the control shaft.

This exerts a cushioned downward pressure on the post 111 or 112 and consequently a pressure on one end or the other of the blade 103. In case the blade 103 engages an obstruction or an unusually hard object or surface, it may move upwardly to pass such obstruction by a compression of one or the other or both of the springs 127.

By an opposite rotary movement of the hand wheels 115 and 116 the leveling blade 103 may be raised, the stems 125 and 126 exerting an upward pull on the standards 111 and 112 through the set collars 129.

By combining the smoothing and leveling blade 103 with the elevating, conveying and dumping apparatus, I have provided a machine which is useful for grading, leveling and surfacing roads or highways. By the use of this machine, a load of earth can be picked up and deposited in any desired place without loss of time and the smoothing and leveling blade will be effective to level and smooth off the load which was previously deposited when the next load is discharged, thus resulting in a further saving of time and labor.

In the combination machine, the draft chain 40 for the scraper pan is adjustably connected to a hook 131 carried by the draw beam 105 of the auxiliary frame.

I claim as my invention:

1. A machine of the character described,

- comprising a frame, an axle rotatably mounted therein, traction wheels on said axle, a scraper pan arranged below the frame, links pivotally connecting said pan with the frame, flexible draft means connected with the forward end of the pan and adjustably attached to the forward end of the frame, drums loosely mounted on said axle, draft elements fixed to and adapted to be wound on said drums, 5 pulleys on said frame above the pan, said draft elements being extended over said pulleys and connected to said pan, clutch members fixed to said axle adjacent said drums, means for causing an operative engagement 10 of said clutch members with the drums for elevating said pan as the machine is advanced, together with ratchet and pawl devices for normally preventing reverse rotation of said drums and thereby holding the pan in elevated position, a rock shaft journaled in the 15 frame, a lever on said rock shaft, cranks on said rock shaft, and links pivotally connecting said cranks with said pawls for simultaneously releasing the pawls from the ratchets. 20
2. A machine of the character described, comprising a frame, an axle rotatably mounted therein, traction wheels on said axle, a scraper pan arranged below the frame, links 25 pivotally connecting said pan with the frame, flexible draft means connected with the forward end of the pan and adjustably attached to the forward end of the frame, drums loosely mounted on said axle, draft elements 30 fixed to and adapted to be wound on said drums, pulleys on said frame above the pan, said draft elements being extended over said pulleys and connected to said pan, clutch members fixed to said axle adjacent said 35 drums, means for causing an operative engagement of said clutch members with the drums for elevating said pan as the machine is advanced, the last named means including a lever, a trip rod journaled adjacent said 40 lever and formed with an extension, a hook on said lever adapted to engage said extension, and a downwardly projecting arm on said trip rod adapted to be engaged by the scraper pan in its upward movement to oscillate the trip rod 45 and cause said projection to press against the trip rod and cause said projection to press against said hook for throwing the lever to inoperative position. 50
3. In a machine of the character described, a scraper pan open at one end, a gate hinged 55 at its upper margin for closing said open end, a lifting lever fulcrumed at one end on said gate, bell crank levers fulcrumed on said gate below the lifting lever, pivotal connections between said bell cranks and the lifting lever, 60 latch rods pivoted to said bell cranks, detent means on the walls of said pan for engagement by said latch rods, and means for oscillating said lifting lever to withdraw the latch rods and permit the gate to open. 65
4. In a machine of the character described, 70 a scraper pan open at one end, a gate hinged at its upper margin for closing said open end, a lifting lever fulcrumed at one end on said gate, bell crank levers fulcrumed on said gate below the lifting lever, pivotal connections between said bell cranks and the lifting lever, 75 latch rods pivoted to said bell cranks, detent means on the walls of said pan for engagement by said latch rods, and means for oscillating said lifting lever to withdraw the latch rods and permit the gate to open, said detent means being formed with inclined strike faces and said latch rods being capable of lateral oscillation to permit them to reenter said detent means after engaging said strike faces. 80
5. In a wheel scraper, a scraper pan, a clutch controlled means for elevating said pan, a lever adapted for actuation to place the clutch devices in engagement, a trip rod journaled adjacent said lever and formed with an extension, a hook on said lever adapted to engage said extension, and a downwardly projecting arm on said trip rod adapted to be engaged by the scraper pan in its upward movement to oscillate the trip rod 85 and cause said projection to press against said hook for throwing the lever to inoperative position. 90
